UNITED STATES PATENT OFFICE.

CHARLES MONROE MINTON, OF PHILOMATH, OREGON.

FLUSH TANK.

Application filed July 14, 1922. Serial No. 574,937.

To all whom it may concern:

Be it known that I, CHARLES M. MINTON, a citizen of the United States, and resident of Philomath, in the county of Benton and 5 State of Oregon, have invented certain new and useful Improvements in Flush Tanks, of which the following is a specification.

This invention relates to flush tanks for water closets and it consists in the combinations, constructions and arrangements herein described and claimed.

An object of my invention is to provide a tank of the character described which affords facilities for supplying desired quantities of water to an associated part and which includes improved automatic means for controlling the flow of water from the tank to insure the maintenance of a predetermined quantity of water within the tank, while the 20 latter is inactive.

Other objects and advantages will be apparent from the following description, and the novel features of the invention will be particularly outlined in the appended claims.

25 My invention is illustrated in the accompanying drawings, forming a part of this application, in which—

Figure 1 is a perspective view showing a practical embodiment of the invention operatively applied.

Figure 2 is an enlarged longitudinal vertical section through the tank exhibited in Figure 1.

Figure 3 is a section along the line 3—3 of Figure 2.

Figure 4 is a fragmentary end elevation of a float comprised in the device, showing also certain elements appurtenant thereto, and

40 Figure 5 is a view showing in side elevation a fragmentary portion of the float exhibited in Figure 4, together with a spring catch and other elements associated therewith.

45 In carrying out my invention, I provide a tank designated generally at T which is supported in a relatively elevated position in any suitable manner and is connected by a delivery conduit D to a closet bowl B which is positioned at a lower level than the tank, as is usual. A supply conduit S extends horizontally from a wall connection K with a source of water supply to a point directly above the tank T and then extends vertically downward through the upper part 50 of the tank T into the interior of the latter,

as will hereinafter appear. A valve V is preferably provided in the supply conduit S between the tank and the wall connection and may be of any suitable type of construction.

The tank T comprises an outer casing 1 which is preferably made of wood and is open at its upper end. The walls of the outer casing 1 are relatively thick. Closely interfitting the outer casing 1 so that the upper end of the walls thereof are flush with the upper ends of the corresponding walls of the casing 1, is an inner casing 2 made of metal of relatively thin gauze. A block 3 extending transversely of the tank at one end thereof is superimposed at its ends upon the side walls of the casing 1 and upon one end wall of the latter, being secured in position by means of screws 4 or the like. 70 The vertical portion of the supply pipe S extends through the block 3 and depends within the interior of the inner casing 2 to a point adjacent to but short of the bottom of the inner casing, as best seen in Figure 80 2. A valve 5 provided in the supply conduit S adjacent to the lower end of the latter controls the flow of liquid therethrough into the tank T. The valve 5 has a horizontal stem portion 6, to the outer end 85 of which is pivotally attached an operating arm 7. The operating member 7 is of bar-like formation and has the end thereof remote from the valve 5 positioned between upstanding lugs 8 on a plate 9 which is an 90 integral part of a rod 10 adapted to a tubular holder 11 which is fixedly secured upon the upper face of a float 12. The bar 7 is attached by a horizontal pivot 13 to the lugs 8 and both the bar 7 and the rod 11 are 95 capable of limited movement relatively to each other about the axis of the pivot 13.

The float 12 is provided with pairs of spaced vertical guide members 14, 14 at opposite ends thereof, which guide members 100 are substantially V-shaped in cross sectional contour and are adapted to slidably engage vertical guide members or rails 15 which are arranged in pairs at opposite sides of the tank adjacent to one end of the latter, being secured to the inner side walls of the inner casing 2 in any suitable known manner. The arrangement is such that the float 12 is free to move vertically in response to the rise and fall of a liquid within the tank but is held against any appreciable lateral or horizontal movement relatively to the tank. 110

Rests in the form of shelves 16 secured by rivets 17 to the side walls of the inner casing 2 limit the downward movement of the float and support the latter in its lowermost position above the level of the bottom of the inner casing. An upward movement of the end of the arm 7 remote from the valve 5 will be caused by upward movement of the float 12 from its lowermost position. This upward movement of the arm 7 causes a movement of the valve 5 from open toward closed position and the valve 5 will be completely closed when the float is adjacent to the upper end of the tank, as illustrated in Figures 2 and 3, whereupon further upward movement of the float is prevented.

It is to be observed at this point that the valve stem 6 is formed with a pair of spaced apart integral plate extensions or ears 18, 18 between which the adjacent portion of the bar 7 extends. The ears or extensions 18, 18 are provided with aligned openings 19 therethrough with which the openings 20 of a series of openings formed through the bar 7 to extend transversely thereof will register successively as the bar 7 is moved about the axis of the valve stem 6. The bar 7 may be releasably locked against movement about the axis of the valve stem 6 independent of the extensions 18, 18 by means of a locking pin 21 projected through the openings 19 and a selected one of the openings 20. The angular relation of the bar 7 to the horizontal when the valve 5 is in closed position can thus be varied within limits and the quantity of water permitted to pass into the tank T prior to the closing of the valve upon upward movement of the float 12 thus regulated.

An outlet pipe 22 extends through the bottom of the tank and is secured to the inner casing 2 in any suitable manner to provide a liquid-tight connection therewith.

The upper end of the outlet pipe 22 extends vertically within the tank above the level of the bottom of the tank and is formed at its upper end to provide a seat 23 for a closure or flush valve disk 24. A gasket 25 in the form of a ring made of a compressible material, such as rubber is carried upon the lower face of the disk 24 in position to engage the seat 23 and thus provide a liquid tight fit between the valve disk and its seat. A bar 26 is secured at 27 to the valve disk 24 and extends diametrically of the latter intermediate of the ends of the bar. The bar 26 is pivotally supported at 28 intermediate of one end thereof and the connection at 27 upon a support 29 which is upstanding from the bottom of the tank. A float 30 is fixedly attached to the bar 26 at the end thereof remote from the valve disk 24. The free end portion of the bar extends between spaced vertical portions 31, 32 of bars having horizontal portions 33 and 34 respec-

tively. The horizontal portion 33 has an upturned end 35 attached to a side wall of the inner casing 2. The horizontal portion 34 is superimposed upon the portion 33 and can be secured to the latter in adjusted position thereon by means of a bolt and nut arrangement 36, whereby the space between the vertical portions 31 and 32 can be varied to accommodate bars 26 of different thicknesses and to release such bars. Depending flanges 37 formed on the horizontal portion 34 straddle the portion 33 and hold the latter against lateral movement relatively to the portion 34.

The vertical portion 31 of the one guide bar described extends to the bottom of the tank and is secured at 37' to the bottom of the inner casing 2. The portion 32 of the other bar extends laterally adjacent to its lower end at an appreciable distance above the bottom of the tank to provide a horizontal stop 38 against which one side of a substantially U-shaped portion 39 of a spring catch 40 abuts. The web of the U-shaped portion of the spring catch 40 extends vertically in substantial alignment with the portion 32 and one arm of the U-shaped portion extends along the bottom of the tank, being fashioned adjacent to its end at 41 to provide a seat for a holding pin 42 which is removably attached to the bottom wall of the inner casing 2 in any suitable manner, as at 43. The upper horizontal arm of the substantially U-shaped portion of the spring catch extends adjacent to the side wall of the tank which is proximate to the end of the lowermost arm, and is merged into an inclined portion 43' which inclines toward the proximate side wall and is secured to the latter at its upper end, as indicated at 44. A shoe or projection 45 upon the float 12 is adapted to engage the inclined portion 43' of the spring catch upon a movement of the float downwardly to effect a lateral shifting of the web portion and the upper arm of the U-shaped spring catch against the action of the lowermost arm of the catch, whereupon the web portion of the spring catch will be moved away from the vertical portion 31 of the one guide bar for a purpose which will hereinafter be set forth.

63 designates a bail or handle attached to the upper side of the float 12 whereby the latter can be lifted.

From the foregoing description of various parts of the device, the operation thereof may be readily understood. The bar 26 is connected adjacent to its free end by means of a link or connecting rod 46 to an intermediate pivoted operating member 47 having a vertically shiftable handle portion 48 extending through a vertical slot 49 in one side of the tank. A chain or like flexible member, not shown, depends from the

outer end of the handle 48 to a position accessible to an operator below the tank. Upon a downward movement of the handle 48, the intermediately pivoted member 47 5 will be swung in such manner as to lift the free end of the bar 26, thereby moving the valve 24 from its seat and permitting liquid from the tank to flow through the outlet pipe 22. The latter is threaded for connection 10 with the delivery conduit D. Upon a lowering of the water level within the tank, the float 12 moves downward, carrying with it the rod 10 and operating the bar 7 to open the valve 5, thereby permitting the water 15 from the supply conduit to flow into the tank. When the free end of the bar 26 was moved upward in the manner described between the vertical guide portions 31 and 32, the web portion of the substantially 20 U-shaped spring catch was permitted to move toward the portion 31 under the actuation of the lowermost arm of the U-shaped catch, so that the bar 26 will be supported adjacent to its free end upon the uppermost 25 arm of the U-shaped catch. When the float 12 has descended a predetermined distance, the inclined portion 43' of the spring catch will be swung laterally on account of the engagement thereof with the shoe or projection 45 and the web portion of the spring 30 catch will be moved away from the portion 31 of the guide bar so that the bar 26 is permitted to move between the web portion of the spring catch and the lower part of 35 the portion 31. The valve disk 24 will be swung downward into position upon the seat 23 to close the outlet 22 when the bar 26 is released and the float 30 is moved upward by reason of a rise of water level 40 within the tank. As a safety measure, a projection or shoe 51 is provided upon the underside of the float 12 in position to contact the free end of the bar 26 upon continued downward movement of the float and 45 to move the bar 26 and the valve disk 24 downward to effect the seating of the valve disk 24 before the float 12 has reached the limit of its movement downwardly. The float 12 is provided with a suction chamber 50 52 formed by a continuous flange 53 depending from the bottom thereof and being open at its lower end. An air vent 54 is formed through the flange 53 adjacent to the juncture of the latter with the bottom wall of 55 the float. The float 30 is likewise formed with a suction chamber 55, which suction chamber is open at its lower end and is provided with an air vent 56 through the walls thereof at its upper end. After the device 60 is placed in operation, the suction chambers 52 and 55 normally remain filled with water and the downward movement of the floats are thus facilitated upon lowering of the water level within the tank.

65 The supply conduit extends from an over-

head source of supply through the upper part of the tank adjacent to the bottom of the tank and very little noise, if any, is thus occasioned by the flow of water to the tank to fill the latter, since the discharge end of 70 the supply conduit is below the water level within the tank at all times. A refill tube 57 of conventional construction extends from the lower end of the supply conduit to discharge into the upper end of an overflow 75 pipe 58. The latter comprises a vertical portion positioned adjacent to one side wall of the tank and extending from a point adjacent to the upper end of the tank to the bottom and then extends along the bottom to 80 the outlet pipe 22, with which it communicates at 59. A strap 60 or the like is provided to hold the vertical portion of the overflow pipe in juxtaposed relation to a side wall of the tank. A lid or cover 61 85 which may be a thin metal sheet, is secured upon the tank by means of screws 62 or the like.

Obviously, my invention is susceptible of embodiment in forms other than that illustrated in the accompanying drawings, and I therefore consider as my own all modifications of the forms of the device disclosed herein, which fairly fall within the scope 90 of the appended claims.

I claim:

1. A tank of the character described comprising a container body adapted to hold a liquid and being provided with an inlet and with an outlet through the bottom thereof, a vertically movable float within the container and adapted to rest upon a liquid therein, means operated by the float for controlling the inlet, a closure for the outlet, a pivoted arm secured intermediately to said closure, a lever and link arrangement connected to said arm at one end thereof and having a portion extending exteriorly of the container body, whereby said closure can be lifted from closing position upon manual 100 operation of the lever and link arrangement, and a float upon the end of the bar remote from that attached to the lever and link arrangement for returning the closure to 105 closed position.
2. A tank of the character described comprising a container body adapted to hold a liquid and being provided with an inlet and with an outlet through the bottom thereof, a vertically movable float within the container and adapted to rest upon a liquid therein, means operated by the float for controlling the inlet, a closure for the outlet, a pivoted arm secured intermediately to said closure, a lever and link arrangement connected to said arm at one end thereof and having a portion extending exteriorly of the container 110 body, whereby said closure can be lifted from closing position upon manual operation of the lever and link arrangement, and a float upon the end of the bar remote from that attached to the lever and link arrangement for returning the closure to 115 closed position.
3. A tank of the character described comprising a container body adapted to hold a liquid and being provided with an inlet and with an outlet through the bottom thereof, a vertically movable float within the container and adapted to rest upon a liquid therein, means operated by the float for controlling the inlet, a closure for the outlet, a pivoted arm secured intermediately to said closure, a lever and link arrangement connected to said arm at one end thereof and having a portion extending exteriorly of the container 120 body, whereby said closure can be lifted from closing position upon manual operation of the lever and link arrangement, and a float upon the end of the bar remote from that attached to the lever and link arrangement for returning the closure to 125 closed position.

float upon the end of the bar remote from that attached to the lever and link arrangement for returning the closure to closed position, a spring catch inherently actuated to 5 releasably engage the pivoted bar upon movement of the closure from closing position to prevent a return movement of the closure operating bar, and means carried by the first named float for engaging the spring 10 catch upon a determined downward movement of the float to effect the release of the closure operating bar.

3. A tank of the character described comprising a container body adapted to hold 15 a liquid and being provided with an inlet and with an outlet through the bottom thereof, a vertically movable float within the container and adapted to rest upon a liquid therein, means operated by the float for 20 controlling the inlet, a closure for the outlet, a pivoted arm secured intermediately to said closure, a lever and link arrangement connected to said arm at one end thereof and

having a portion extending exteriorly of the container body, whereby said closure can 25 be lifted from closing position upon manual operation of the lever and link arrangement, a float upon the end of the bar remote from that attached to the lever and link arrangement for returning the closure to closed position, a spring catch inherently actuated to 30 releasably engage the pivoted bar upon movement of the closure from closing position to prevent a return movement of the closure operating bar, means carried by the 35 first named float for engaging the spring catch upon a determined downward movement of the float to effect the release of the closure operating bar, and other means carried by the first named float in position to 40 engage the closure operating bar upon a further downward movement of the float to positively move the bar in such manner as to effect the return of the closure to closing position.

CHARLES MONROE MINTON.
